FLOWER POT HOLDER

Joseph Holt, 99 Kingsboro Road, Rochester, N.Y.

Filed Nov. 18, 1960, Ser. No. 62,896

Term of patent 14 years

(Cl. D35—3)

FIG. 2

FIG. 1 is a side elevational view of a flower pot holder, showing my new design; and

FIG. 2 is a top plan view thereof.

I claim:

The ornamental design for a flower pot holder, as shown.
